UNITED STATES PATENT OFFICE

HENRY LIFSHUTZ, OF BROOKLYN, NEW YORK

SHOE AND METHOD OF MAKING SAME

Application filed December 26, 1929. Serial No. 416,646.

This invention relates to new and useful improvements in shoes and methods of making the same, particularly ladies' shoes of the high or French heel type, although the invention is applicable to the manufacture of ladies' and men's shoes of any type, the primary object of the invention being to produce a shoe which is so constructed as to readily support the weight of the wearer on the heel portion without twisting or turning to either one side or the other, thus retaining the shoe in its natural and normal shape, regardless of the tendency of the wearer to twist or lean to one side or the other.

15 A further object of the invention resides in constructing a shoe which has the sole, the shank portion and the heel base all formed from a single blank of material.

Still another object of the invention resides in providing an improved means for securing the upper and the counter to the sole, shank and heel base blank.

A still further object resides in providing a shoe which is simple and durable in construction, comparatively inexpensive to manufacture and one which will be very efficient in use.

With these and numerous other objects in view, my invention consists in the novel features of construction, combination and arrangement of parts as will be hereinafter referred to and more particularly pointed out in the specification and claims.

In the accompanying drawings, forming a part of this application:

Figure 1 is a plan view of a blank from which the sole, shank portion and heel base are formed, the same being cut in the desired shape for use;

40 Figure 2 is an edge elevation thereof;

Figure 3 is a bottom plan view of a shoe in the course of construction, showing the manner in which the upper and counters are secured to the heel, shank and sole portions of the blank, prior to turning;

Figure 4 is a perspective view of the shoe as disclosed in Figure 3, prior to turning;

Figure 5 is a similar view, with parts cut away and parts in section, to clearly illustrate the relation of the elements and par-

ticularly showing the inside of the shoe prior to turning;

Figure 6 is a perspective view of the shoe after it is turned and prior to the securing of the high heel thereon;

Figure 7 is a similar view after the heel is secured in place;

Figure 8 is a vertical longitudinal section through the shoe as shown in Figure 7;

Figure 9 is a vertical transverse section as seen on the line 9—9 of Figure 8;

Figure 10 is a transverse section as seen on the line 10—10 of Figure 8;

Figure 11 is an enlarged detail section illustrating the manner in which the upper is secured to the sole; and

Figure 12 is a similar view illustrating the manner in which the counter is secured to the shank portion of the sole.

My invention is applicable to the manufacture of ladies', children's and/or men's shoes, not only of the turned type but also to the type of shoes known as the welt type, and those made under what is known as the "McKay" process, or those made under the "compo" process. For purposes of illustration, however, I have shown and will describe the invention as applied to a turned shoe.

The present prevailing styles for women include a high heel or what is known as the French heel, and in the ordinary manufacture of shoes with heels of this type, difficulty has been encountered in the manufacture of a shoe which will positively withstand the weight of the wearer which may cause twisting or leaning of the body of the shoe to one side or the other. This is primarily due to the fact that the heel receives substantially all the weight of the wearer and substantially every wearer has a tendency to lean to one side or the other, or if no tendency is present, the high heel itself will cause the wearer to throw the weight to one side or the other, thus causing the shoe to lose its natural shape. My invention contemplates the manufacture of a shoe which will overcome these difficulties in a most simple and efficient manner.

In describing my invention, I shall refer to the drawing in which similar reference characters designate corresponding parts through-

out the several views and in which 1 designates a sole provided with an elongated shank portion 2 which is also formed integral with a heel base 3. These elements 1, 2 and 3 are cut from a single blank of leather and the formation of this shank portion 2 integral with the elements 1 and 3 is the most essential feature of the invention.

Stitched along the dotted lines, as indicated in Figure 1 within the outer marginal edges of the elements 1, 2 and 3, is the upper which, as shown, comprises the inner lining 4 and the outer skin or leather 5 between which is supported the counter 6. In the views of the drawing illustrating the shoe prior to turning, the inner lining and outer facing or skin are in reverse position, obviously. The marginal portions of the sole 1 and heel base 3 beyond the line of stitching are folded back and flattened against the sole and heel base, respectively, in the usual manner, and as clearly shown in Figure 3 and more clearly illustrated in Figure 11, the latter showing the sole after the shoe has been turned. The counter 6, however, is secured to the shank 2 in a manner which would permit the marginal portions of said shank to be bent inwardly against one another forming substantially a T between the counter and the inner and outer facings of the latter, this T shank being shown in Figure 12 in inverted position after the shoe is turned. The shank 2 being secured in this fashion provides a particularly rigid support between the sole 1 and the heel base 3, as appears obvious.

The heel base 3 is split longitudinally, after the shoe is turned, so as to form a fly or leaf-like portion 7 which may be shaped according to the character and shape of heel which is to be applied to the base 3. The heel 8 is then secured to the base 3 in the usual or any preferred manner, I having shown the securing means in the form of a screw 9 and nail 10. Of course, the usual shank or stiffener 11 is secured on the inside of the sole through the same means as secures the heel in place, as clearly shown in Figure 8 of the drawings. A liner 12, as usual, is inserted inside of the shoe and the fly or leaf 7, shaped to conform to the shape of the heel 8, is adhesively or otherwise applied to the inner flat wall as clearly shown in Figures 7 and 8 of the drawings.

With a shoe constructed in this manner, it will be seen that a rigid connection is had between the sole and the heel portions thereof. When a person wearing a high heeled shoe walks with a shoe constructed in this manner, the entire weight of the wearer will not be thrust upon the heel but will be somewhat directed forwardly and thus the weight is more evenly distributed over those portions of the shoe which are constructed to support said weight. Even if all of the weight is applied to the heel portion of the shoe, the par-

ticular construction is such as to rigidly support the walls of the shoe and prevent turning or twisting of said walls which is most undesirable and the cause of most complaints against the wearing of shoes with high heels. The many objections now made to the shoes constructed under prevailing process may be obviated through the construction of a shoe in accordance with this invention.

From the foregoing description of the construction of my improved shoe and the description of the method of making the same, it will be seen that I have provided a simple, inexpensive and efficient means for carrying out the objects of the invention.

While I have particularly described the elements best adapted to perform the functions set forth, it is apparent that various changes in form and in the minor details of construction may be resorted to, without departing from the spirit or sacrificing any of the principles of the invention.

Having thus described my invention, what I claim is:

1. In a shoe of the class described, a sole, a heel base, an elongated shank portion integral with said sole and heel base and connecting same together, an upper stitched to said sole, shank and heel base portions, said upper including counters, said shank portion being bent to form a T in cross section and secured between the inner edges of said counters to form a rigid support between said sole and heel base, and a heel secured to said heel base.

2. In a shoe of the class described, an upper including a pair of counters, a sole, a heel base, an integral shank portion, of elongated design connecting said sole with said heel base, said shank portion being bent and looped to form a T in cross section, the inner opposed edges of said counters abutting and secured to the vertical portion of the T-shaped shank, to provide a rigid supporting connection between said sole and the heel base, and a heel secured to said heel base.

3. The method of constructing a turned shoe comprising assembling an integral sole, having an elongated shank and a heel base, turning in the edges of the shank to form substantially a T in cross section, and stitching an upper, including counters, to the sole, shank and heel base, the opposed inner edges of the counters being abutted and secured to the vertical portion of the T-shaped shank, prior to turning.

4. In a turned shoe, a sole, a heel portion, counter portions secured to said sole and heel portion, and a relatively narrow and elongated shank-forming strip of substantially uniform width connecting said sole and heel portions and secured in interposed relation between the adjacent edges of said counter portions.

5. In a turned shoe, a sole, a heel portion,

counter portions secured to said sole and heel portion, and a relatively narrow elongated strip of substantially uniform width formed integral with said sole and heel portion, said 5 strip being interposed between and firmly secured to the adjacent edges of said counter portions to form a rigid shank support for the shoe.

6. The method of constructing a turned 10 shoe comprising assembling a sole structure having a heel and forward portion connected by a relatively narrow and elongated shank-forming strip of substantially uniform width, with the upper portion of the shoe, and a 15 counter having portions abutting and secured to said strip, prior to turning.

7. The method of constructing a turned 20 shoe comprising assembling a sole structure having a heel and forward portion connected by an integral and relatively narrow elongated shank-forming strip of substantially uniform width, with the upper portion of the shoe, and a counter having portions abutting and secured to said strip, prior to turning.

25 In testimony whereof I affix my signature.
HENRY LIFSHUTZ.
